(57) **CLAIM**

The ornamental design for a docking station with wireless speakers for an electronic device, as shown and described.

DESCRIPTION

FIG. 1 is a front elevational view of a docking station with wireless speakers for an electronic device showing my new design;

FIG. 2 is a rear elevational view of the docking station in FIG. 1;

FIG. 3 is a left side view thereof;

FIG. 4 is a right side view thereof;

FIG. 5 is a top plan view thereof;

FIG. 6 is a bottom plan view thereof; and

FIG. 7 is a perspective view thereof.

FIG. 8 is a front elevational view of another embodiment of a docking station with wireless speakers for an electronic device;

FIG. 9 is a rear elevational view thereof the docking station in FIG. 8;

FIG. 10 is a left side view thereof;

FIG. 11 is a right side view thereof;

FIG. 12 is a top plan view thereof;

FIG. 13 is a bottom plan view thereof; and,

FIG. 14 is a perspective view thereof.

The broken lines in the drawings depict part of the docking station with wireless speakers for an electronic device that form no part of the claimed design.
